CROSS-SLIDE MECHANISM

Arthur H. Jobert and Jerome J. Taravella, New Britain, Conn., assignors to The New Britain Machine Company, New Britain, Conn., a corporation of Connecticut

Application November 26, 1940, Serial No. 367,168

10 Claims. (Cl. 74—96)

Our invention relates to improvements in slide mechanisms, and particularly to cross-slide mechanisms for machines, such as lathes, multiple-spindle screw machines, and the like.

It is customary in machines of the character indicated to employ camming means for moving the forming and other tools operated from cross slides. Hitherto, the flexibility or adaptability of such machines to producing various sizes of work has either been limited to work which may be turned out with one set of cross-slide cams, or it has been necessary to have a multiplicity of interchangeable cams to adapt the machine to the type of work being produced. Not only is it uneconomical to have to carry a large stock of such cams on hand, but a large amount of labor is involved in the replacement of these parts according to the variety of work to be produced.

We propose a relatively simple device which will eliminate the necessity of changing cross-slide cams and which will adapt the machine to a wide variety of operations and uses.

It is an object of the invention to provide improved cross-slide feeding means in machines of the character indicated.

Another object is the provision in such machines of improved means for jump-feeding tools up to the work prior to a relatively slow working feed.

It is another object of the invention to provide means for deriving a variety of reciprocal strokes within a constant or substantially constant amplitude of reciprocation.

A further object is the provision of means for variously relating the jump to the feed stroke in a machine of the character indicated without changing the total period for both jump and feed motions.

It is also an object of this invention to provide means for obtaining various lengths of jump and feed strokes without altering the total of both the jump and the feed stroke.

Still another object resides in provision of improved means for producing a plurality of tool-feeding motions without disturbing the cam or other means from which the tool-feeding motion is derived.

Other objects and various features of the invention will become apparent to those skilled in the art from a reading of the following specification in conjunction with the drawings included herewith, which show, for illustrative purposes only, a preferred embodiment of the invention, and in which—

Fig. 1 is an end elevation, partly broken away,

showing a conventional multi-spindle machine having cross-slides operated through the medium of a device illustrative of this invention;

Fig. 2 is a detailed view, partly broken away, and illustrating features of the invention, the mechanism being shown in position corresponding to a fully retracted position of the cross-slide tools;

Fig. 3 is a partly broken-away, sectional plan of parts shown in Fig. 2, and as viewed substantially on the planes 3—3;

Fig. 4 shows an even greater enlarged detailed front elevation of features of the invention;

Fig. 5 is a sectional view of parts shown in Fig. 4 and taken in generally vertical, central planes.

Fig. 6 is a detailed elevation, similar to Fig. 2, but illustrating the relation of parts after the jump and jut prior to a gradual feed into the work;

Fig. 7 is another detailed elevation, similar to Figs. 2 and 6, but illustrating the relation of parts at the end of the working stroke;

Fig. 8 is an enlarged isometric view of a detail, 25 At the outset let it be understood that the terms, "slide" and "cross-slide," as hereinafter used in this specification, of course refer not only to the slides of the general nature shown in the drawings, but also include all tool-advancing means, 30 such as tool carriers which may depend upon rotation to feed a tool, end-working tool slides, and the like.

Our invention in the form illustrated includes an adjustable means disposed in the customary linkage for operating cross-slides from a main cam shaft. By means of adjustments which may easily be made, it is possible to provide for an adjustable jump or relatively fast feed up to the work, followed by an adjustable relatively slow 35 cutting feed in the work—all with one standard driving cam or other drive means.

For illustrative purposes, and by way of example only, we have shown our invention in Fig. 1 in conjunction with an automatically indexing eight-spindle machine. Four cross-slides 45 holding forming or cutting-off tools, as is customary, are positioned for working in the four spindle positions shown in this elevation. In the form shown all cross-slide units are mounted on the frame 5 of the machine. Slides 6 and 7, for the spindles 8 and 9, respectively, are mounted for operation independently of each other, as will later be clear. Slides 10 and 11, for the spindles 12 and 13, respectively, are likewise 50 mounted as a unit, but, in the form shown, they 55

operate together and with the same feeding motion.

Motion for jump-feeding and work-feeding the cross-slides is derived from any desired feeding means, and in the form shown, cams, carried by cam disks 14 and 15, are provided for this purpose. However, we propose to provide additional means between the cam and cross-slide. This additional means, which forms part of the subject of the present invention, is illustrated more clearly in the enlarged detail views of Figs. 2, 3, 4, and 5.

In the form shown mechanism according to our invention forms a connection between the cam-follower arm 16 and a crank 17, which in turn acts directly on the tool-slide to propel or retract the same. This link or mechanism is preferably a plate 18, which is slidable in a generally longitudinal direction, as determined by the ways or tracks 19 and 20, respectively. The guideways 19 and 20 are shown as formed on the block or base 21. Retaining guide-plate members 22 and 23, extending out and over the cut-out portions defining tracks 19 and 20, respectively, are held securely in place by bolts 24, which bolts further serve to seat the base 21 rigidly on the frame 5 of the machine. The plate 18 is provided with opposed parallel edges 25 and 26, so as to fit slidably within the corresponding tracks 19 and 20. The cam-follower 16 and the plate 18 are pivotally connected as by means of the pin 27. The lever 17 is actuated by the plate 18 through means, such as an adjustable connecting pin-roller 29. A generally vertically extending dovetail slot 28 is preferably provided on the plate 18 in order to accommodate a dovetail on the pin-roller 29 which may thus be adjustably secured to plate 18, as by a clamping bolt 31, in a definite position for control purposes which will later become apparent.

It will be seen how longitudinal reciprocal motion, imparted to plate 18 by the cam-follower 16, may be transmitted to crank or lever 17 through pin-roller 29, operating in a corresponding roller-receiving slot 30 on crank 17; and it will be clear that variation in the generally vertical disposition of pin-roller 29 within slot 28 will, for a definite and constant stroke of the cam-follower rod, impart varied strokes to the crank 17. The clamping bolt 31 is preferably readily accessible, as through the slot 32, and various numerical graduations (see Figs. 1 and 4) may be made on the crank 17 to permit greater accuracy in setting up, as will be clear.

In order to provide for two different speeds of the cross-slide from one given stroke of the cam-follower arm 16, we make possible an additional motion of the plate 18. We terminate the longitudinal guided motion, which has been described above, by running a pin 33, fixed to the plate, against a stop; and thereafter cam-follower-arm motion may be translated into a rotary motion of plate 18 about pin 33, as will be clear. After pin 33 abuts the end of a slot 34 in base plate 21 to form a point about which rotation may take place, an arcuate edge 35 of plate 18, arcuate about the pin 33, has reached the end of the straight track 20 (see Fig. 4) and is positioned to slide within the correspondingly recessed arcuate track portion 36 of the base plate 21. A portion of the upper edge of the plate 18 is cut off so that rotary motion thereof is permitted without fouling the straight track 19, as will also be clear.

It will be noted that, depending upon the location of the pin-roller 29 in the dovetail slot 28, the crank 17 may be given any movement, ranging from zero to a maximum, during the period of rotary motion of plate 18. Zero movement will be obtained when pin-roller 29 is positioned directly above, and concentric with, the stopping pin 33; and a maximum movement will result from securing the pin 29 at the bottom of slot 28.

It will be understood that the type of motion obtained with our "wobble-plate" device is a relatively fast feed or transposition of crank 17 throughout the first part of the cam-follower-arm stroke, that is while the plate 18 slides on the guides 19, 20; and a variable, relatively slow feed throughout the remainder of the same stroke, that is while the plate 18 rocks about the pivot 33. In the machine shown, use may be made of the first fast feed to obtain a jump feed or relatively rapid advance of a tool up to the work, and of the variable gradual motion for feeding the tool.

Upon retraction, or rather, on the return half of the cycle through which the cam-follower-arm travels, plate 18 will go through the same series of motions—and, of course, in reverse order to that followed for feed; that is, there will be a slow retraction of the tool in the immediate vicinity of the work, followed by a fast or jump retraction rapidly to clear the tool from the work to permit free indexing. Jamming the "wobble plate" 18 within the rotary track, as the jump retraction begins, is avoided by provision of a guiding stop 37, positioned to abut the generally arcuate upper left edge 38 of plate 18 at all times except when plate 18 is in alignment with the straight ways 19 and 20 to slide back freely along the same. At this instant the guide stop 37 will be opposite a corresponding slot 39 in plate 18, and free guided sliding is permitted down the substantially straight ways 19 and 20.

The cycle of operations and successive positions of the "wobble plate" 18 will be clear from an examination of Figs. 2, 6, and 7, in that order. The roller-pin 29 has been fixed in an intermediate position along the dovetail slot 28 for a relatively small feed, as will be understood. Fig. 2 shows the relationship of the driving members just prior to jump-feeding the tool up to the work, that is, the cam-follower-roll 40 on cam-follower-arm 16 is about to engage the jump-feeding surface 41 of cam 14. With the fast jump-feeding motion derived therefrom, the parallel edges 25 and 26 on plate 18 slide straight along, as guided within and by tracks 19 and 20, until the top portion of cam surface 41 is reached. At this point (Fig. 6) jump-feeding has been accomplished, the guide stop 37 has left engagement with the guide slide 39, pivot pin 33 has abutted the end of slot 34, and the curved surface 35 of plate 18 is in position to slide within the arcuate grooved track 36. As the cam-follower-arm 16 is slowly urged further by the working-feed surface 42 of cam 14 throughout that portion of the stroke (from the position shown in Fig. 6 to that in Fig. 7), the "wobble plate" is forced to rotate, and thus to carry pin-roller 29 through an arc (which in the case shown is relatively small) and at the same time to impart a reduced feeding motion to the cross-slide by means of the sector gear 43 on crank 17 engaging a rack on the cross-slide.

After the end of the cam-feed surface 42 has been reached, the cam-follower-roll 40 is imme-

diately engaged by the draw-back surface 44 of cam 14 in order quickly to clear all tools from the work so that no work or tools will be fouled upon indexing, which in the form shown is permitted to take place within almost a half-revolution of cam 14 by the long dwell which may be observed on the cam-surface 44.

Several forms of cross-slide to which the "wobble plate" adjustable link may be adapted are shown in Fig. 1 in connection with an eight-spindle machine. It will be clear that the form which has been described in detail has referred to mechanism for operating cross-slides 10 and 11 at spindle stations 12 and 13, respectively. In the form shown, slides 10 and 11 are unitarily mounted and are guided and supported in their sliding motion by means of the sleeve 45, which fits slidably around a guiding stub-shaft 46. A rack 47, affixed to the cross-slide unit 10-11, engages the sector gear 43 of arm 17 to pick up the feed motions which have already been described in detail. Thus, the single cam 14, operating through the "wobble plate" 18 and the rack and sector gears, may operate two forming tools with feed which may be controlled by adjusting the pin-roller 29, made readily accessible by means, such as a sliding door panel 48.

Fig. 1 further shows how the two additional slides 6 and 7 may be controlled to have motions independent of each other, although they are driven from the same cam shaft (which in the form shown is geared to rotate in 1:1 ratio with the shaft of cam 14). Considering operation of slide 7, the linkages concerned are essentially the same as those for slides 10 and 11. The cam-follower-arm 49 reciprocates in a generally vertical direction to actuate the wobble plate unit 50 and thus adjustably to rock the slide-control double-arm or bell-crank 51 for jump and work feeding, as will be clear from an appreciation of the pivotal connection of bell-crank 51 to slide 7 at, say, the point 52.

In a similar manner, motion for slide 6 may be picked up by cam-follower arm 53 from the same cam surface on cam 15 as was used for cam-follower arm 49. This motion is again communicated to "wobble-plate" link 54 and then transmitted by double-arm-crank means 55 to slide 6 at the pivotal connection 56 between the latter two members.

It will be clear that by making the setting of the pin-roller on "wobble-plate" 54 different from that on plate 50, two independent and distinctly different feeds will be offered slides 6 and 7, although they may both be controlled and operated by identical or similar cams on disk 15.

It will be observed, from a viewing of Figs. 2, 6, and 7, that, no matter what the vertical disposition of the pin-roller 29, the total of the jump and the feed stroke may be maintained constant by employing a cam 14 of suitable throw for the particular location of crank 17. At the start of the jump stroke (Fig. 2) it will be noted that the pin-roller slot 30 on crank 17 overstands the dovetail slot 28 on the "wobble-plate." From such a disposition of these two slots it will be clear that the tool starting position, as determined by the angularity of crank 17, will be the same no matter where pin-roller 29 happens to be located in these slots. The same may be said of the finish position—that is, at the end of the feed stroke (see Fig. 7)—at which point the two slots 28 and 30 overstand one another once again. It follows from this relationship that, no matter what the vertical disposition of pin-roller 29 in

these slots, the tool will stop feeding at the same point. In other words, the tool starting and finish points being the same whatever the location of pin-roller 29 along slot 28, the total of jump and feed strokes may be the same—such a relationship only arising if the cam 14 has been designed to give a proper stroke, as has been indicated above.

It is, of course, to be understood that the form shown for the track through which the "wobble-plate" slides is merely for illustrative purposes. Track courses, giving rise to motions other than the straight and rotary travel involved in the instant example, may be employed, and these need not even be of a discontinuous nature to accomplish substantially the same result as is here obtained—that is, a relatively fast jump-feed followed by a working feed.

Furthermore, while a cam means, in particular the cam 14, has been shown as the driving means for cross-slide operation, various other motion-driving means may be used; and such other motion-generating means may include cranks, eccentrics, or other like means.

Therefore, it is to be understood that, although the invention has been shown in conjunction with a pair of cross-slides operated as a unit, the features of the invention may be adapted to machines having any configuration of slides, including a machine having all cross slides operating independently of each other—and even several cross slides to a spindle.

We have provided relatively simple means for accomplishing great savings in the labor, time, and cost of setting up machines of the general character indicated. Although this means has been particularly described in a preferred form in connection with cross slides on a multiple-spindle machine, it is, of course, not so intended to be limited; and it is to be understood that various changes, additions, modifications, and omissions may be made within the scope of the invention as defined in the appended claims.

We claim:

1. A rocking member for transmitting motion from a driving member to a driven member, pivot means for said rocking member, substantially straight line guide means for said rocking member, driving means for said rocking member for bodily traversing said pivot means with said rocking member along said guide means and for rocking said rocking member about said pivot means, and means for pivotally connecting a driven member to said rocking member, for the purpose described.

2. A rocking member for transmitting motion from a driving member to a driven member, pivot means for said rocking member, driving means for said rocking member for bodily traversing said pivot means with said rocking member along a substantially straight path and for rocking said rocking member about said pivot means, and means for pivotally connecting a driven member to said rocking member at varying distances from said pivot means.

3. A rocking member for transmitting motion from a driving member to a driven member, said rocking member having pivot means, means for driving said rocking member for bodily traversing a part of said rocking member including said pivot means and for rocking said rocking member about said pivot means until said rocking member reaches the final end point in its driven motion, a driven member, and means for connecting said driven member to said rocking

member at varying distances from said pivot means while said rocking member and driven member are both at the end points of their movement, whereby the motions transmitted to said driven member by said rocking member will be varied relatively to each other and said driven member will always be moved to the final end point by said rocking member regardless of said relative movements transmitted to said driven member.

4. In a device of the character indicated, a rocking member for transmitting motion from driving means to driven means, means for causing said rocking member to be traversed bodily and subsequently rocked about pivot means to a final limit of movement, driven means, and means for pivotally connecting said driven means to said rocking means at various distances from said pivot means without changing the relative positions of said driven means and rocking member at the limit of movement, for the purpose described.

5. In a device of the character indicated, rocking means for transmitting motion from driving means to driven means, means for driving said rocking means including means to cause said rocking means to be bodily traversed and rocked about pivot means, a driven member, adjustable pivot means for connecting said driven member and said rocking means, said pivot means being adjustable on said rocking means and said driven means along paths on each which are coincident when said rocking means and said driven means are substantially at the final limit of movement in at least one direction.

6. In a device of the character indicated, rocking means for transmitting motion from driving means to a driven means, means for translating spaced points on said rocking means along parallel paths and subsequently stopping translating movement of one of said points and rocking the other of said points about said stopped point, and means for connecting a driven member to said rocking means, for the purpose described.

7. In a device of the character indicated, rocking means for transmitting motion from driving means to driven means, means for bodily traversing said rocking means and rocking one point on said rocking means about another point to a final end point of movement, a driven member,

5 and means for pivotally connecting said driven member and rocking means at various points at different distances from the rocking point of said rocking means, said various points of pivotal connection being respectively coincident with each other when said rocking means and driven member are at the end points of movement of both of said members.

8. In a device of the character indicated, a 10 rocking member, limited guide means for guiding said rocking member and constraining the same to move bodily in a straight path, engageable pivot means for restraining one part of said rocking member when said rocking member is disengaged from said guiding means, a driving member pivotally connected to said rocking member whereby said driving member will bodily move said rocking member when in engagement with said guiding means and will rock said rocking member about said pivot means when said rocking member has been moved beyond said guiding means, and driven means connected to said rocking means.

9. In a device of the character indicated, a 15 rocking member for transmitting motion from driving means to driven means, fixed guiding means and fixed pivot means, said rocking member being engageable with and guided by said guiding means until said rocking member is moved into engagement with said fixed pivot means, after which said rocking member may rock about said fixed pivot means, a pivotally mounted driven member, and means for pivotally connecting said rocking member to said pivotally mounted driven member.

10. In a device of the character indicated, a 20 rocking member for transmitting motion from a driving to a driven member, guide means for guiding said rocking member along a fixed path of movement, fixed pivot axis means engageable by said rocking member only when moved a predetermined distance along said fixed path and to a point where said rocking member is freed from said guide means and is free to rock about said pivot axis, and driven means driven by said rocking member during movement along said fixed path and while rocking.

ARTHUR H. JOBERT.
